UNITED STATES PATENT OFFICE.

ALBERT JOHN SCHOLTES, OF MOBILE, ALABAMA.

DESIGN FOR RIBBON FABRIC.

Application filed July 7, 1923. Serial No. 6,729. Term of patent 7 years.

To all whom it may concern:

Be it known that I, ALBERT J. SCHOLTES, a citizen of the United States, residing at Mobile, in the county of Mobile and State of Alabama, have invented a new, original, and ornamental Design for Ribbon Fabric, of which the following is a specification, reference being had to the accompanying drawing, forming part thereof, in which:—

The figure represents a fragmentary portion of ribbon fabric with the ornamental design of this invention.

I claim:

The ornamental design for ribbon fabric, as shown.

ALBERT JOHN SCHOLTES.
